(57) **CLAIM**

The ornamental design for a photography tripod, as shown and described.

DESCRIPTION

FIG. 1 is a first perspective view of a photography tripod showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the photography tripod thereof;

FIG. 10 is an enlarged view of the selected portion in FIG. 1; and,

FIG. 11 is an enlarged view of the selected portion in FIG. 2.

The broken lines shown in the drawings depict portions of the photography tripod in which the design is embodied that form no part of the claimed design.
